SNAP-MOVEMENT-VALVE MECHANISM.

1,314,244.

Specification of Letters Patent. Patented Aug. 26, 1919.

Application filed June 11, 1918, Serial No. 239,405. Renewed June 19, 1919. Serial No. 305,397.

To all whom it may concern:

Be it known that I, CHARLES F. BRAND, a citizen of the United States of America, and resident of Wheeling, county of Ohio, 5 and State of West Virginia, have invented certain new and useful Improvements in Snap - Movement - Valve Mechanisms, of which the following is a specification.

This invention relates broadly to valves, 10 and more particularly to that type of control valve which is opened and closed by a substantially instantaneous, or snap, movement.

The primary object of the invention is to provide a valve mechanism of relatively 15 simple and inexpensive construction adapted for association with and to be controlled by temperature regulators or thermostats of common forms.

A further object is to provide a thermos- 20 tatically controlled valve mechanism provided with means whereby it may be adjusted to any desired degree of sensitivity, adapting it for use under widely varying line pressures and conditions.

25 A still further object is to provide a valve control mechanism, designed primarily for gas, steam, hot water and hot air supply lines, which is efficient and reliable in its operation and by means of which the valve 30 is actuated to move from its wholly closed position to wide-open position with an instantaneous, or snap, movement.

A further object within the contemplation 35 of the invention is to provide a valve mechanism of the character mentioned embodying an operating lever adapted to be actuated from valve-closing to valve-opening position by the diaphragm or movable member of a temperature regulator or thermostatic 40 and which requires only a slight movement of such actuating member to effect the relatively greater length of shifting movement required thereof.

In describing the invention in detail, 45 reference is herein had to the accompanying drawing, of which the single figure is a side elevation of the invention.

While it will be understood that the invention is readily applicable to various uses 50 or purposes, it is especially adapted for use in gas, steam, and hot-water heating systems, and the explanation which follows

will be generally directed to a description thereof as applied to such systems.

Referring to the drawing, 1 indicates a 55 valve body of a common type adapted to be disposed in a gas, steam, hot-water, or other supply line. The shiftable valve member 2 is carried by the lower end of a vertically disposed stem 3 which has its upper end 60 projected a suitable distance above the usual packing gland 4. Carried by and preferably adjustable upon the projecting end of said valve-stem is a head 5 which is connected to a lever 6 by means of two connected pivoted links 7 and 8 which in the normal position of the mechanism occupy positions substantially in alinement with said stem. The link 8 is pivoted to said lever at a point in advance of the rear end 65 of the latter, which end is pivoted to the upper end of a link 10 that has its opposite end pivoted upon the upright arm 9^a of a yoke-shaped member 9. The yoke 9 is seated in fixed position upon the top of the 70 valve body 1 and has the upper end of its opposite upright arm 9^b located a suitable distance below the overhanging lever 6, as shown.

Pivots mounted intermediate its ends 80 upon the arm 9^b is a rocker member 11 which has its lower end disposed rearward of said arm and which has fixed thereto a rod or pin 12. Said pin projects forward through a relatively large hole in said arm 85 9^b and has threaded upon its free end an adjusting nut 13 between which and the opposing face of said arm is a pin-encircling spiral spring 14. Connecting the upper end 90 of said rocker member 11 to the lever 6 at a point located a suitable distance rearward of the center line of said arm 9^b are two connected pivoted links 15 and 16 which, in the closed position of the valve, are relatively disposed at an angle slightly less than 95 a right angle and which, in the open position of the valve, are disposed approximately in alinement.

A link 17 has one end pivoted upon the pivot pin 18 which serves to connect the link 100 10 to the yoke arm 9^a and has its opposite end pivoted upon the pivot pin 19 which connects the links 7 and 8.

As is obvious, the spring 14 when placed

under tension by adjustment of the nut 13 exerts a force upon the rocker member 11 which tends to thrust the latter toward the dotted line position indicated in the drawing in which the lower end of said member is seated against the adjacent face of the yoke arm 9^b. To assume such position the upper end of the rocker member must move rearward—a movement which is permitted 5 either when the links 15 and 16 are relatively shifted toward the inclined alined position indicated in dotted lines or when they are shifted from right-angular relation toward the acute-angle position shown in full lines 10 in the drawing. Closing movement of said links in jack-knife fashion beyond said full line position is effectually prevented, due to the fact that the lever 6 is supported against further downward movement by the substantially alined links 7 and 8 which are anchored by the link 17 against forward swinging movement, and downward swinging movement of the forward end of said lever is prevented by the link 10 which connects its rear end to the yoke arm 9^a. Due 15 to the acute-angled relation of the said links 15 and 16, no amount of force applied to the rocker member 11 by the spring 14 or otherwise will serve to initiate movement of said links in the opposite direction, or 20 toward the approximately alined relation necessary to be assumed thereby to permit said lever to reach the limit of its elevation. It follows, therefore, that an initial lever- 25 actuating force is required to effect opening of the valve. This force is supplied by the movable member of a suitably located temperature regulator or thermostat (not shown) which is connected to the free end of 30 the lever 6, as by a suspension chain 20.

A weight 21 is carried by the lever, the same being designed as a counterbalance which overcomes the resistance to lowering movement of said lever offered by the spring 45 14 when the sustaining force exerted by the regulator or thermostat is removed or becomes practically negligible. The tension of said spring is preferably adjusted so that, when the lever occupies its elevated position, the force which it exerts will be slightly less than that which would be necessary to maintain said lever with said weight 21 in elevated position. Consequently, but slight force is required to be exerted by the regulator or thermostat to effect the elevation of 50 the movable parts of the device.

To provide for the necessary shifting movements of the lever 6 with a minimum of movement of the regulator or thermostat, a 60 novel form of connection is had between said lever and its weight 21. Said connection consists of an upright bar 22 interposed between the chain 20 and the weight 21, and a link 23 interposed between the end of 65 said lever and said bar. Said link 23, which

has one end pivotally connected to the end of said lever and its opposite end in like manner connected to said bar at a point intermediate the ends of the latter, has its said ends bifurcated with said lever and said bar 70 received in the bifurcations thereof. The web 23^a located between the bifurcations of said link has that wall thereof which faces the edge of the constantly vertical bar 22 disposed at such an angle that, when the lever is in its lowered position, its lower edge is abutted by said edge of the bar, and when the lever occupies its wholly elevated position, its upper edge is abutted by said bar. Thus, said link possesses at its front 80 end only a slight range of movement as compared with that of the end of the lever to which its rear end is attached, and, consequently, the vertical distance through which the weight or counterbalance and its suspension elements, including the movable member of the temperature regulator, must pass to effect the requisite shifting of said lever is relatively short, as is clearly illustrated in the drawing.

In practice, assuming that the valve and its hereinbefore-described actuating parts occupy the normal closed positions shown in full lines in the drawing, when the temperature drops to a point below that to which 95 the regulator has been adjusted, a gradually elevating force against the tension of the spring 14 is thereby applied through the interposed parts to the lever 6. With initial elevating movement of its front end the 100 lever swings rearward slightly, a movement which is permitted by the pivotal connection therewith of the links 16, 8 and 10. Due to this rearward swinging, a lifting tension is not placed upon the valve stem 105 through the links 7 and 8 until an approximately half-way point in the movement of said lever is reached. When such approximately half-way point is reached by the lever, the links 15 and 16 have been moved 110 against the tension of the spring 14 from their normal positions toward alined position such a distance that their center of resistance is passed, whereupon the spring exerts a force which instantaneously acts to 115 thrust the parts from said half-way position to the extreme limit of elevation indicated in dotted lines in the drawing, carrying therewith the member 2 of the valve, with an instantaneous, or snap, movement, from 120 its fully seated valve-closing position to its wide-open position.

On the other hand, as the temperature rises above a predetermined point, the tension placed upon the suspension chain by 125 the regulator gradually relaxes and the counterbalance weight actuates the lever to descend gradually against the resistance offered by the spring until, at a point where the center of resistance to closing movement 130

of the links 15 and 16 with respect to each other is reached, the spring supplements the counterbalance weight and the parts are thereby actuated to drop instantaneously, or 5 with a snap, to valve-closing position.

From the foregoing it will be understood that, once properly adjusted, the operation of the device is automatic throughout. Obviously, the spring tends to resist initial 10 movement of the parts from either of the two limits of movement and facilitates final movement in both directions.

What is claimed is—

1. A snap movement valve mechanism comprising a valve having a vertically movable stem, a yoke mounted on said valve, a rocker member pivoted upon one arm of said yoke, a lever having flexible link connection with said rocker member, a flexible 15 link connection between the rear end of said lever and the other arm of said yoke, a flexible link connection between said valve stem and said lever at a point intermediate the first two above-mentioned link connections, and means exerting a yielding force 20 upon said rocker member whereby said lever is adapted to be held against movement from either of its opposite limits for maintaining said valve seated at said opposite limits.
2. A snap movement valve mechanism comprising a valve having a vertically movable stem, a yoke mounted on said valve, a rocker member pivoted upon one arm of said yoke, a lever having flexible link connection 25 at a point intermediate its ends with said rocker member, a flexible link connection between the rear end of said lever and the other arm of said yoke, a flexible link connection between said valve stem and said 30 lever at a point located rearward with respect to the first mentioned connection, and yieldable means resisting movement of said lever from both of its opposite limits of movement.
3. A snap movement valve mechanism comprising a valve having a vertically movable stem, a yoke mounted on said valve, a rocker member pivoted upon one arm of said yoke, a lever having flexible link connection 35 at a point intermediate its ends with said rocker member, a flexible link connection between the rear end of said lever and the other arm of said yoke, a flexible link connection between said valve stem and said 40 lever at a point located rearward with respect to the first mentioned connection, and yieldable means resisting movement of said lever from both of its opposite limits of movement.
4. A snap movement valve mechanism comprising a valve having a vertically movable stem, a yoke disposed in fixed relation to said valve and having a rocker member 45 pivoted to one arm thereof, a lever having

pivotal relation with said rocker member through two pivotally connected links which at one limit of movement of said lever occupy approximately alined relation and which at the opposite limit of said movement are disposed in acute-angled relation, a flexible connection between the rear end of said lever and the opposite yoke arm, a flexible connection between said valve stem and said lever at a point located rearward of the 75 said link connection, and a spring associated with said rocker member, said spring acting to yieldingly resist initial movement of said connected links from both of their named 80 positions and acting subsequent to such initial movement to impart to said links a final instantaneous thrust whereby said valve is actuated to assume its opposite extreme positions with a snap movement.

5. A snap valve mechanism comprising a 85 valve having a vertical stem, a yoke mounted over said valve, a rocker member pivotally carried by one arm of said yoke, a weighted lever having flexible connection at its rear end with the opposite arm of said 90 yoke and having flexible connected-link connection at a point intermediate its ends with said rocker member, a flexible connection between said valve stem and said lever at a point between the first two above-mentioned 95 connections, and means acting through said link connection upon said lever and tending to resist initial movement of the latter from both of its extreme positions and to facilitate the final part of such movement. 100

6. A snap valve mechanism comprising a valve having a stem, a yoke mounted over said valve, a rocker member pivotally carried by one arm of said yoke, a weighted lever having flexible connection at its rear 105 end with the opposite arm of said yoke and having flexible connected-link connection at a point intermediate its ends with said rocker member, a flexible connection between said valve stem and said lever at a point 110 between the first two above-mentioned connections, means acting through said link connection upon said lever and tending to resist movement of the latter from both of its extreme positions and to facilitate the 115 final part of such movement, and means connected to said lever whereby an initial elevating movement may be imparted to the latter.

7. A snap valve mechanism comprising a 120 valve having a stem, a yoke mounted over said valve, a rocker member pivotally carried by one arm of said yoke, a lever having flexible connection at its rear end with the opposite arm of said yoke and having flexible 125 connected-link connection at a point intermediate its ends with said rocker member, a flexible connection between said valve stem and said lever at a point between the first two above-mentioned connections, means 130

acting through said link connection upon said lever and tending to resist movement of the latter from both of its extreme positions and to facilitate the final part of such movement, and a counterbalance weight having pivoted link connection with the front end of said lever.

8. A snap valve mechanism comprising a valve having a stem, a yoke mounted over said valve, a rocker member pivotally carried by one arm of said yoke, a lever having flexible connection at its rear end with the opposite arm of said yoke and having flexible connected-link connection at a point intermediate its ends with said rocker member, a flexible connection between said valve stem and said lever at a point between the first two above-mentioned connections, means acting through said link connection upon said lever and tending to resist movement of the latter from both of its extreme positions and to facilitate the final part of such movement, a counterbalance weight including an upright member, a link interposed between said upright member and the front end of said lever and having pivotal connection with both, said upright member

having a portion adapted to engage and coact with a portion of said link whereby the range of swinging movement of the latter with respect to said upright member is limited.

9. In a snap movement valve mechanism, a valve, a stem carried by said valve, a pivoted lever having pivoted connection at a point intermediate its ends with said stem, means connected to said lever tending to resist movement of the latter from both of its extreme positions and to facilitate the final part of such movement, a vertically movable counterbalance weight, and a link having pivotal connection at one end with the free end of said lever and at the other with said weight, said link having a portion adapted to engage and coact with an adjacent portion of said weight whereby the range of swinging movement of the link with respect to the latter is limited.

In testimony whereof, I affix my signature in presence of two subscribing witnesses. 50
